Primary Examiner—Sandra L. Morris*Assistant Examiner*—Cheri Cohen*Attorney, Agent, or Firm*—Parsons & Goltby; Robert A. Parsons; Michael W. Goltby**[57] CLAIM**

The ornamental design for a ball return attachment for basketball hoop, as shown and described.

DESCRIPTION

FIG. 1 is a perspective view of a ball return attachment for basketball hoop showing my new design therefor;

FIG. 2 is a top plan view;

FIG. 3 is a right side elevational view;

FIG. 4 is a rear elevational view;

FIG. 5 is a front elevational view;

FIG. 6 is a left side elevational view;

FIG. 7 is a bottom plan view;

FIG. 8 is a perspective view of a second alternate embodiment;

FIG. 9 is a top plan view;

FIG. 10 is a right side elevational view;

FIG. 11 is a rear elevational view;

FIG. 12 is a front elevational view;

FIG. 13 is a left side elevational view; and,

FIG. 14 is a bottom plan view.
